(57) **CLAIM**

The ornamental design for a signal converter, as shown.

DESCRIPTION

FIG. 1 is a front, bottom and right side perspective view of a signal converter showing a first embodiment of our design; FIG. 2 is a rear, top and left side perspective view thereof; FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof;

FIG. 9 is a front, bottom and right side perspective view of a signal converter showing a second embodiment of our design;

FIG. 10 is a rear, top and left side perspective view thereof;

FIG. 11 is a front view thereof;

FIG. 12 is a rear view thereof;

FIG. 13 is a top plan view thereof;

FIG. 14 is a bottom plan view thereof;

(Continued)

FIG. 15 is a left side view thereof; and,
FIG. 16 is a right side view thereof.

1 Claim, 16 Drawing Sheets
